UNITED STATES PATENT OFFICE.

CHARLES S. C. ROCK, OF NEW YORK, N. Y.

WASTE AND VENT SYSTEM.

1,086,938.

Specification of Letters Patent. Patented Feb. 10, 1914.

Application filed December 17, 1912. Serial No. 737,209.

To all whom it may concern:

Be it known that I, CHARLES S. C. Rock, a subject of the King of Great Britain, and a resident of the city of New York, borough 5 of Manhattan, in the county and State of New York, have invented a new and Improved Waste and Vent System, of which the following is a full, clear, and exact description.

10 The invention relates to house systems of water distribution, and its object is to provide a new and improved waste and vent system having a plumber's fitting designed to connect the soil pipe with the vent pipe 15 and adapted to connect with bath tubs, sinks, water closets and other fixtures to be drained and vented, the arrangement being such that the plumber can readily assemble the parts and make the desired connections, 20 and that proper drainage and venting is insured.

In order to accomplish the desired result use is made of a plumber's fitting embodying a soil pipe member forming a portion 25 of the soil pipe, and a vent duct or a plurality thereof extending integrally from the side of the soil pipe member, the said vent duct or ducts extending upwardly and being provided with a lateral inlet or inlets, 30 and the said duct or ducts having a lateral terminal and a vent pipe member forming a part of the main vent pipe and engaged by the said terminal.

A practical embodiment of the invention 35 is represented in the accompanying drawings forming a part of this specification, in which similar characters of reference indicate corresponding parts in all the views.

Figure 1 is a plan view of the combined 40 soil pipe, drainage and vent fitting as applied, the soil and vent pipes and the walls of the building being shown in section; Fig. 2 is a side elevation of the combined soil pipe, drainage and vent fitting provided 45 with two vent ducts and a separate inlet for drainage, parts being in section; Fig. 3 is a side elevation of the combined soil pipe, drainage and vent fitting applied to a soil pipe and having a single vent duct and a 50 drainage inlet; Fig. 4 is a similar view of the same and showing three vent ducts forming integral portions of the soil pipe member and terminating in a single terminal; Fig. 5 is a like view of the fitting provided 55 with a single vent duct; Fig. 6 is a similar view of the same and showing the fitting

with two vent ducts for water closet and bath connection and partly shown in section; and Fig. 7 is a similar view of the same and showing the fitting with two vent ducts for connection with a closet and sink, the upper end of the vent ducts being shown in section.

In the preferred form of my invention, as 60 illustrated in Figs. 1 and 2, use is made of a combined soil pipe, drainage and vent fitting having a soil pipe member A forming a portion of the soil pipe B. From one side of the soil pipe member A extend vent ducts C and D having their upper ends leading 65 to a common terminal E extending laterally and arranged for engagement with a vent pipe member G forming part of the main vent pipe H. The terminal E is preferably threaded and screws into a correspondingly- 70 threaded hub F on the vent pipe member G. The vent ducts C and D are provided intermediate their ends and at any desired height 75 with lateral openings I and J, of which the opening I is connected with a sink I' (see 80 Fig. 1), while the opening J is connected with a water closet J' to drain the same and to provide the desired venting. The vent ducts C and D may be spaced apart but are preferably a unitary structure, as indicated 85 in Fig. 2.

From the side of the soil pipe member A extends a branch inlet K having a hub K' adapted to be connected by a pipe K² with a fixture K³ which is vented to a hub L 90 formed on the main vent pipe member G. For the purpose described use is made of a pipe N (see Fig. 1) from which leads a branch pipe N' to the fixture K³, and, if desired, other fixtures, for instance, a bath 95 tub O, may be connected by a pipe O' with the pipe K² for drainage purposes, and by a branch pipe O² with the pipe N. Other fixtures, such as a bath tub P and a water closet Q, may be connected with a second 100 combined soil pipe drainage and vent fitting arranged on a second soil pipe B', the said second fitting having on its vent ducts C and D a common terminal E connected by a pipe R with the pipe N, it being understood that the bath tub P connects by a pipe P' with the lateral opening I of the second fitting, and the water closet Q connected with the lateral opening J of this second fitting by a pipe Q'. By the arrangement described a single vent pipe H can be 105 used for properly venting a large number 110

of fixtures which drain into the soil pipes B and B'.

In the modified form shown in Fig. 3, the combined soil pipe, drainage and vent fitting consists of a soil pipe member A' forming part of the main soil pipe B², and from one side of the said member A' extends integrally and upwardly a vent duct D' having a lateral threaded terminal E' for engagement with the main vent pipe member G. The duct D' is provided with a lateral opening J² for connection with a water closet, and from the side of the member A' extends a drainage inlet K⁴ having a hub K⁵ for connection with a fixture to be drained, the same as above described in reference to the drainage inlet K and its hub K'.

In the modified form shown in Fig. 4, the soil pipe member A² forms a portion of the soil pipe B³ and is provided with integral vent ducts C', D² and S, all leading to an integral lateral terminal E² arranged for connection with the vent pipe member G. The vent duct C' is provided with a lateral opening I² for connection with a sink, the duct D² is provided with a lateral opening J³ for connection with a water closet, and the vent duct S is provided with a lateral opening S' for connection with a bath tub or similar fixture.

In the simplest form of my invention as shown in Fig. 5, the soil pipe member A³ forms part of the soil pipe B⁴ and is provided at one side with an integral upwardly-extending vent duct D³, the lateral terminal E³ of which is adapted to connect with the vent pipe member G. The vent duct D³ is provided with a lateral opening J⁴ for connection with the water closet.

In the modified form shown in Fig. 6, the soil pipe member A⁴ forms part of the main soil pipe B⁵, and from the said member A⁴ extends the vent ducts D⁴ and S² leading to a common terminal E⁴ arranged for connection with the vent pipe member G. The duct D⁴ is provided with a lateral opening J⁵ for connection with a water closet, and the lateral opening S³ in the duct S² is arranged for connection with a bath tub.

In the modified form shown in Fig. 7, the soil pipe member A⁵ forms part of the soil pipe B⁶ and is provided with vent ducts C² and D⁵ having a common terminal E⁵ for connection with the vent pipe member G. The vent duct pipe C² is provided with a lateral opening I³ for connection with a sink, and the vent duct D⁶ is provided with a lateral opening J⁶ for connection with a water closet.

It is understood that by the arrangement described the lateral openings in the vent ducts may be at one side or the other according to the location of the fixtures to be drained and vented.

It will further be noticed that the lateral openings may be at any point in the height of the vent ducts but are separate from the soil pipe member.

The fitting shown and described can be cheaply manufactured and arranged to suit existing conditions, and serves to enable the plumber to readily make the proper connection with the fixture to be drained and vented.

Having thus described my invention, I claim as new and desire to secure by Letters Patent:

1. A plumbing system, having a main soil pipe, a main vent pipe and a plumber's fitting embodying a soil pipe member forming a portion of the soil pipe, and a vent duct extending integrally from the side of the said soil pipe member, the said vent duct extending upwardly and parallel and in close proximity to the said main soil pipe, the said vent duct being provided with a lateral inlet, and the said duct having a lateral terminal at its upper end, and a vent pipe member forming part of the said main vent pipe and engaged by the said duct terminal.

2. A plumbing system having a main soil pipe, a main vent pipe and a plumber's fitting embodying a soil pipe member forming a portion of the soil pipe, and a plurality of vent ducts extending integrally from the side of the said soil pipe member, the said vent ducts extending upwardly and parallel and in close proximity to the said main soil pipe, each vent duct being provided with a lateral inlet, the said vent ducts terminating in a single lateral end, and a vent pipe member forming part of the said main vent pipe and engaged by the said duct terminal.

3. A plumbing system having a main soil pipe, a main vent pipe and a plumber's fitting embodying a soil pipe member forming a portion of the soil pipe, and a plurality of vent ducts extending integrally from the side of the said soil pipe member, the said vent ducts extending upwardly and parallel and in close proximity to the said main soil pipe, each vent duct being provided with a lateral inlet, the said vent ducts terminating in a single lateral end, an inlet duct connected integrally with the said soil pipe member and terminating in a hub for connection with a drainage pipe, and a vent pipe member forming part of the said main vent pipe and having lateral connections, one for receiving the said duct terminal and the other for receiving a vent duct from the fixture with which the said inlet is connected.

4. A plumbing system having a main soil pipe, a main vent pipe and a plumber's fitting embodying a soil pipe member forming a portion of the soil pipe, a vent duct extending integrally from the side of the said

soil pipe member, the said vent duct extending upwardly, and parallel and in close proximity to the said main soil pipe, the said vent duct being provided with a lateral inlet, the said vent duct having a lateral terminal, and a vent pipe member forming part of the said main vent pipe, the said lateral terminal of the vent duct and the said vent pipe having a threaded connection.

5. A plumbing system having a main soil pipe, a main vent pipe and a plumber's fitting embodying a soil pipe member forming a portion of the soil pipe and a vent duct 15 extending integrally from the side of the said soil pipe member, the said vent duct extending upwardly and being provided with a lateral inlet and the said vent duct having a lateral integral terminal at its upper end, a vent pipe member forming part 20 of the said main vent pipe, and a lateral connection between the said terminal and the said vent pipe member.

6. A plumbing system having a main soil pipe, a main vent pipe and a plumber's fitting embodying a soil pipe member forming a portion of the soil pipe and a vent duct 25 extending integrally from the side of the said soil pipe member, the said vent duct extending upwardly and being provided

with a lateral inlet and the said vent duct having a lateral integral terminal at its upper end, a vent pipe member forming part of the said main vent pipe and provided with a lateral hub, and a connection connecting the said terminal with the hub of the said vent pipe member.

7. A plumbing system comprising a plurality of main soil pipes, a single main vent pipe and plumber's fittings, one for each main soil pipe, and each embodying a soil pipe member forming a portion of the corresponding soil pipe, and a vent duct extending integrally from the side of the said soil pipe member, the said vent duct extending upwardly and being provided with a lateral inlet and the said vent duct having a lateral integral terminal at its upper end, a vent pipe member forming part of the said main vent pipe, and provided with a lateral hub, and connections connecting the terminals of the said fittings with the said hub of the vent pipe member.

In testimony whereof I have signed my name to this specification in the presence of two subscribing witnesses.
